US00D644906S

(12) **United States Design Patent**
Demers et al.

(10) **Patent No.:** US D644,906 S
(45) **Date of Patent:** ** Sep. 13, 2011

(54) **TOOL HOUSING**

(75) Inventors: **Brian Joseph Demers**, Huntersville, NC (US); **Joseph Allen Berlepsch**, Mooresville, NC (US)

(73) Assignee: **Lowe's Companies, Inc.**, Mooresville, NC (US)

(**) Term: **14 Years**

(21) Appl. No.: **29/357,512**

(22) Filed: **Mar. 12, 2010**

Related U.S. Application Data

(62) Division of application No. 29/318,755, filed on May 27, 2008, now Pat. No. Des. 615,381, which is a division of application No. 29/249,389, filed on Oct. 4, 2006, now Pat. No. Des. 572,558.

(57) **CLAIM**

The ornamental design for a tool housing, as shown and described.

DESCRIPTION

FIG. 1 is a perspective view of a tool housing according to the present invention.

FIG. 2 is a rear elevational view thereof;

FIG. 3 is a top view thereof;

FIG. 4 is a left side elevational view thereof;

FIG. 5 is a bottom plan view thereof;

FIG. 6 is a front elevational view thereof; and,

FIG. 7 is a right side elevational view thereof.

The broken lines shown in the drawings are for the purpose of illustrating unclaimed portions of the tool housing and form no part of the claimed design.
